(57) **CLAIM**

The ornamental design for a support head for video and photographic apparatuses, as shown and described.

DESCRIPTION

FIG. 1 is a top front left side perspective view of the support head of the present design, the portion in broken lines showing attachment means of the support head to a video photographic apparatus, which may be of any suitable type and therefore is not part of the present design;

FIG. 2 is a top plan view of the support head of the present design, the portion in broken lines forming no part of the present design;

FIG. 3 is a front view of the support head of the present design, the portion in broken lines forming no part of the present design;

FIG. 4 is a left side view of the support head of the present design, the portion in broken lines forming no part of the present design;

FIG. 5 is a right side view of the support head of the present design, the portion in broken lines forming no part of the present design;

FIG. 6 is a back view of the support head of the present design, the portion in broken lines forming no part of the present design;

FIG. 7 is a bottom plan view of the support head of the present design;

FIG. 8 is a top back left side perspective view of the support head of the present design, the portion in broken lines forming no part of the present design;

FIG. 9 is a bottom front left side perspective view of the support head of the present design, the portion in broken lines forming no part of the present design; and,

FIG. 10 is a bottom back left side perspective view of the support head of the present design, the portion in broken lines forming no part of the present design.
